UNITED STATES PATENT OFFICE.

GEORGE RESSLER, OF CANTON, OHIO.

KEY-OPERATED TUBULAR CHIMES.

1,177,537.

Specification of Letters Patent. Patented Mar. 28, 1916.

Application filed July 31, 1914 Serial No. 854,216.

To all whom it may concern:

Be it known that I, GEORGE RESSLER, a citizen of the United States, residing at Canton, in the county of Stark and State of Ohio, have invented new and useful Key-Operated Tubular Chimes, of which the following is a specification.

My invention relates to improvements in musical instruments of the character known as tubular chimes and more especially to that type of chimes adapted to be played by means of a manually operated hammer action.

The object of this invention is to produce a simple and inexpensive device capable of being easily and quickly knocked down for storage purposes.

A further object is to provide a device of the character referred to which may be easily played by those not skilled in music.

A further object is to provide a musical instrument of the character referred to comprising a series of tubular chimes suspended within a frame and adapted to be played upon by means of a manually operated hammer action.

With these objects in view the invention consists in the novel construction and arrangement of parts, hereinafter described, illustrated in the accompanying drawings, and particularly pointed out in the appended claim, it being understood that various changes in the form, proportions, size and minor details of construction may be made without departing from the spirit or sacrificing any of the advantages of the invention.

In the drawings: Figure 1 is a perspective view of an instrument embodying my invention. Fig. 2 is a similar view on an enlarged scale through the key board showing the hammer action. Fig. 3 is a section on line 3—3, Fig. 1. Fig. 4 is a section on line 4—4, Fig. 2. Fig. 5 is an end elevation of a modified form of the device.

Similar numerals of reference indicate corresponding parts throughout the several figures of the drawing.

Referring more specifically to the construction disclosed in Figs. 1 to 4 inclusive of the drawings, the numeral 1 indicates the cross bar, the numerals 2 and 3 the supports of a frame which is carried upon a pair of castings 4, the supports 2 and 3 being screwed into the sockets 5 in said castings. The castings 4 are supported by front and rear legs

6 and 7 respectively, preferably formed of hollow rods or pipes provided with right hand screw threads at their upper extremities adapted to be screwed into the sockets 8 in the castings 4 and with left hand threads at the lower extremities adapted to be screwed into the sockets 9 of the bases 10. Suitable elbows 11 are provided for connecting the cross bar 1 and the supports 2 and 3 which are also preferably formed of hollow rods or pipes.

The board 12 is provided with slots 13 at either end adapted to fit around the supports 2 and 3 and rests upon the castings 4, the screw threaded stems 14 provided upon the casting passing through suitable apertures in the board and wing nuts 15 being provided upon said screw threaded stems to hold the key board firmly upon the castings.

A brace bar 16 is provided to strengthen and give rigidity to the frame of the device and preferably connects the rear legs 7 as shown in Fig. 1. The brace bar is preferably curved as shown in the drawings and its ends are screw-threaded into castings 17 by which means the brace bars are connected to the legs 7, the castings being attached to said legs by means of thumb screws 18.

Upon the underside of the cross bar 1 is a series of spaced supporting hooks 19 from which the chime tubes 20 are suspended by means of the hanging cords 21. The tubes 20 are formed of any desirable metal, preferably of a metal which will give a clear bell-like tone when struck with a suitable instrument. These tubes are made of different lengths in order to produce notes of different pitch. The tubes 20 are located through apertures 22 in the board 12, said apertures being of sufficient diameter to allow a slight movement of the tubes, a lining 23 of felt or other suitable material being placed within the apertures.

The hammer brackets 24 are suspended beneath the key board 12 and connected thereto in any suitable and well known manner. Pivoted at 25 to each of the brackets is a hammer 26 provided with a striking face 27 composed of leather or other suitable material. It will be noticed that the hammer is provided with an off-set portion 28 which brings the striking face in alignment with the center of the chime tube. The upper end of the spring 29 is connected at 30 to the hammer and its lower extremity is connected to the downwardly depending

arm 31 fixed upon the bracket 24. A stop 32 covered with rubber or other suitable sound deadening material is provided for the hammer to contact with when the hammer is in its normal position, and when the hammer is in its normal position, as shown in the drawing it engages the chime tube and holds it slightly out of plumb, the reason for this being hereinafter explained.

10 For the purpose of operating the hammer, a key device is provided consisting of a lever 33 pivoted at 34 to the bracket and provided at its forward end with the key 35 provided with a suitable finger button 36, said key being pivotally attached to the lever and slidably mounted within a thimble 37 located in the key board. Upper and lower stops 38 and 39 respectively are provided to limit the movement of the forward extremity of the lever, a jack 40 being pivoted at 41 to the forward extremity of the lever and provided with a spring 42 which is also connected to the arm 31, a pad 43 of felt or other suitable material being located upon the arm at the points where the springs are connected thereto for the purpose of deadening the sound and obviating the singing of the springs.

When it is desired to play upon any particular chime tube the key corresponding thereto is depressed, thus raising the forward end of the lever 3, the jack 40 thereon contacting with the forward lip of the portion 28 of the hammer, thus throwing the hammer back and out of engagement with the tube. The tube will follow the hammer for a short distance, until it is moved into the vertical position when it will become stationary, the hammer continuing to travel 40 away from the tube. As the pressure upon the key is continued the forward end of the lever will be raised until the jacks pass upward out of engagement with the lip upon the hammer, at which time the spring 29 will pull the hammer against the tube with considerable force, thus causing the tube to vibrate, and producing a musical sound.

Since each of the tubes is hung in such a position that it is normally held out of plumb by the hammer it will be obvious that as the hammer is moved back preparatory to striking a blow upon the tube, the tube will swing into a vertical position, moving toward the hammer as the hammer returns 55 to strike the tube thus issuing a loud, clear and uniform tone upon each operation of the hammer.

A series of numerals are provided upon the board opposite to each of the keys so that a person not skilled in music may easily and readily learn to operate the device. A shield 44 preferably composed of sheet metal ornamented in any desired manner is at-

tached to the board in any suitable and well known manner and depends downwardly 65 therefrom for the purpose of hiding from view the mechanism of the hammer.

In Fig. 5 is shown a side elevation of a slightly modified form of device, the form shown being adapted to be hung upon a 70 wall. In this construction the frame consists of side pieces 45 connected together at their top by means of a board 46 and at the lower extremities by the board 47. The tubes 20^a will be supported in the same manner as those in the first form although in this modified form of the device the tubes would preferably be suspended from hooks placed directly in the board 46, although this detail of the construction is immaterial. 75 A shield 48 preferably of ornamented sheet metal is provided around the board 46 for the purpose of hiding the suspending cords of the tube and a shield 44^a is provided around the board. The construction of the hammers and keys is the same in this form of the device as in the form of the first-mentioned form.

Although the drawings and above specification disclose the best mode in which I have contemplated embodying my invention I desire to be not limited to the details of such disclosure, for, in the further practical application of my invention, many changes in form and construction may be made, as circumstances require or experience suggests, without departing from the spirit of the invention, within the scope of the appended claim.

I claim:

A musical instrument comprising a supporting frame, a board connected to said frame, said board provided with apertures, a series of chime tubes supported by said frame and suspended in the said apertures, 100 a series of brackets connected to said board adjacent said chime tubes, a hammer pivotally mounted upon each of said brackets and holding said chime tubes out of plumb, springs holding said hammer in engagement with said chime tubes, a lever pivotally mounted upon each of said brackets, jacks carried upon the extremities of said levers and adapted to engage said hammers, 105 springs holding said jacks out of engagement with said hammers, keys slidably mounted through said board and connected to said levers, and a screen connected to said board.

In testimony that I claim the above, I 120 have hereunto subscribed my name in the presence of two witnesses.

GEORGE RESSLER.
